US00D671160S

(12) **United States Design Patent**
Lin

(10) **Patent No.:** US D671,160 S
(45) **Date of Patent:** ** Nov. 20, 2012

(54) **PROJECTOR**

(75) Inventor: **Cheng-Yu Lin**, Taoyuan Hsien (TW)

(73) Assignee: **Delta Electronics, Inc.** (TW)

(**) Term: **14 Years**

(21) Appl. No.: **29/425,409**

(22) Filed: **Jun. 22, 2012**

Related U.S. Application Data

(62) Division of application No. 29/390,795, filed on Apr. 29, 2011.

(30) **Foreign Application Priority Data**

(57) **CLAIM**

The ornamental design for a projector, as shown and described.

DESCRIPTION

FIG. 1 is a perspective view of a projector showing my design; FIG. 2 is a front elevational view of FIG. 1; FIG. 3 is a rear elevational view of FIG. 1; FIG. 4 is a left side elevational view of FIG. 1; FIG. 5 is a right side elevational view of FIG. 1; FIG. 6 is a top plan view of FIG. 1; FIG. 7 is a bottom plan view of FIG. 1; FIG. 8 is an enlarged view of the local portion labeled as "8" in FIG. 2; and, FIG. 9 is an enlarged view of the local portion labeled as "9" in FIG. 5.

The broken lines shown in the figures represent portions of the projector that form no part of the claimed design.

1 Claim, 9 Drawing Sheets
